Primary Examiner—Stacia Cadmus(74) *Attorney, Agent, or Firm*—Crowell & Moring LLP(57) **CLAIM**

The ornamental design for a wheel or wheel cover, as shown and described.

DESCRIPTION

This application is related to the following co-pending applications: Ser. No. 29/268,410, filed Nov. 7, 2006; and Ser. No. 29/287,171, filed Jul. 6, 2007.

FIG. 1 is a front view of a wheel or wheel cover according to my novel design; and,

FIG. 2 is a perspective view thereof.

The broken line showing of the rear portion of the rim and the central hub area is included for the purpose of illustrating environment and forms no part of the claimed design.
